Martin Scherer, 52 Lawrence Drive,
North White Plains, N.Y.

Filed Feb. 2, 1962, Ser. No. 68,628

Term of patent 3½ years

(Cl. D29—23)

FIG. 1 is a perspective view of an automobile dashboard ornament showing my new design; and

FIG. 2 is a side elevational view thereof; and

FIG. 3 is a front elevational view thereof.

The side of the article, not shown, is substantially the same as the shown side. The bottom is plain and unornamented.

The rear not shown is substantially the same in appearance as the front shown.

I claim:

The ornamental design for an automobile dashboard ornament, as shown and described.
